FIG. 1

FIG. 2

FIG. 3

FIG. 4

FIG. 5

FIG. 6

FIG. 7

FIG. 8

FIGURE 1 is a perspective front view of a speed control lever for a bicycle embodying the new design;

FIGURE 2 is a perspective rear view thereof;

FIGURE 3 is a side elevation view thereof;

FIGURE 4 is a front elevation view thereof;

FIGURE 5 is a side elevation view thereof taken from the side opposite that shown in FIG. 3;

FIGURE 6 is a rear elevation view thereof;

FIGURE 7 is a top plan view thereof; and

FIGURE 8 is a bottom plan view thereof.

The dominant features of the design reside in the portions shown in full lines.

The broken line showing of FIGS. 1 and 2 has been omitted from FIGS. 3 through 8 for ease of illustration.

I claim:

The ornamental design for a speed control lever for a bicycle or similar article, substantially as shown and described.
